DESIGN FOR A COMBINED FEEDING AND DRINKING BOWL FOR ANIMALS

Stafford Siekert, Whitefish Bay, Wis.

Application April 26, 1937, Serial No. 68,977

Term of patent 3½ years

To all whom it may concern:

Be it known that I, Stafford Siekert, a citizen of the United States, residing at Whitefish Bay, in the county of Milwaukee and State of Wisconsin, have invented a new, original, and ornamental Design for a Combined Feeding and Drinking Bowl for Animals, of which the following is a specification, reference being had to the accompanying drawing forming a part thereof.

In the drawing:

Fig. 1 is a perspective view of a combined feeding and drinking bowl for animals showing my new design; and

Fig. 2 is a sectional view of the bowl taken on line 2—2 of Fig. 1.

I claim:

The ornamental design for a combined feeding and drinking bowl for animals, as shown.

STAFFORD SIEKERT.
